FLUID PROJECTING APPARATUS

Lewis M. McBride, Arcadia, Calif.

Application December 9, 1946, Serial No. 715,050

11 Claims. (Cl. 299—89)

1

This invention relates to a fluid projecting apparatus and more particularly to a device for the projection of a liquid or the suspension of a solid in a liquid, at a high forward and rotational velocity.

In the spraying or projecting of liquids such as insecticides, lacrimators, and the like or of suspensions of solid finely divided toxic or non-toxic agents in suitable carrying liquids, use is commonly made of an auxiliary source of pressure fluid such as various compressed gases to furnish the projecting force. These auxiliary pressure fluids are conveniently introduced to a reservoir containing the liquid or suspension to be discharged thereby forcing the same through an eduction tube and a discharge nozzle.

In U. S. Patent 1,740,471 I described a fluid projecting apparatus of this type in which a pressure operating fluid such as compressed air, oxygen, carbon dioxide or the like was employed to discharge the liquid or suspension from the projecting apparatus. This device operated on a differential pressure principal which permitted the introduction of a certain amount of the pressure operating fluid into the discharging stream to accelerate and disperse the latter. This differential pressure was obtained by allowing a portion of the pressure operating fluid to by-pass the reservoir of the projecting device and pass through an orifice directly into the discharging stream within the eduction tube. The pressure differential induced in this device was a function of the size of this by-pass orifice, which was predetermined as a function of the internal diameter of the eduction tube and the character of the pressure operating fluid.

A limitation inherent in the above described fluid projecting apparatus was the absence of means for controlling the pressure differential. This limitation rendered the operation with various types of pressure fluids variable inasmuch as the character of various ones of such fluids, as for example, oxygen, compressed air, liquid carbon dioxide, etc., differs and the pressure at which they are stored is not uniform. Further it has been found that as the pressure of any type of pressure fluid falls, due to the partial exhaustion of the pressure in the container the operation of the fluid projecting device varies as a result of the fixed size of this bypass orifice. Similar variation in operation is encountered where the liquid in the reservoir is depleted, which reduction causes a corresponding increase in the volume occupied by the pressure fluid within the reservoir resulting in a disproportionate

2

exhaust of the pressure fluid through the bypass port or orifice and a resultant variation of the pressure differential equilibrium. A corresponding change in the nature of the discharge stream naturally results from such a variation in the pressure differential equilibrium. Further no means were provided in the above described apparatus for closing off the eduction tube and bypass orifice so as to prevent undesirable leakage when the pressure of the pressure fluid dropped to an inoperative level or when the device was not in use.

It is an object therefor of the present invention to provide a fluid projecting device which operates automatically and uniformly regardless of the variations in the pressure of the motivating fluid or in the volume of space in the apparatus occupied by the motivating fluid.

It is an additional object of the invention to provide a fluid projecting apparatus in which the ejection of liquid is automatically prevented when the flow of pressure fluid is stopped and which will not leak when not in use regardless of its position.

These and other objects of the invention are accomplished according to the present invention by the provision of a differential pressure type liquid projecting apparatus in which the differential pressure equilibrium is automatically maintained and in which a liquid flow through an eduction tube and nozzle is automatically prevented when the driving pressure falls below a predetermined value.

The apparatus whereby the foregoing ends are accomplished comprises in its simplest embodiment a source of pressure, a liquid reservoir in communication therewith, means for forcing the gas from the pressure source to flow into the liquid reservoir and to thereby force the liquid in the reservoir out through an eduction tube and nozzle in association with the reservoir and a bypass orifice through which a portion of the gas from the pressure source flows directly into the eduction tube, at a point above the liquid level in the reservoir and a spring loaded regulating valve disposed in the eduction tube adjacent to the orifice inlet whereby the flow from the reservoir and the flow of gas from the pressure source through the aforementioned bypass orifice is controlled by the tension exerted on the spring loaded check valve.

The invention may be more clearly understood from the following detailed description thereof taken in relation to the accompanying drawing in which:

Fig. 1 is a side elevation of the fluid projecting apparatus in association with the pressure source;

Fig. 2 is a sectional elevation of the fluid projecting apparatus;

Fig. 3 is a plan view of the apparatus;

Fig. 4 is a side elevation of a modified form of the apparatus showing the reservoir and pressure source in different relationship than that shown in Fig. 1; and

Fig. 5 is a fragmentary sectional elevation of the apparatus of Fig. 4.

In Fig. 1 the reservoir 10 is shown affixed to the pressure source, or cylinder 11 by means of the connecting nipple 12 provided with the set screws 13 and 14.

The pressure source 11 may be of any conventional type and may be provided with substantially any non-toxic gas under pressure such as air, carbon dioxide, nitrogen, or the like, or may be filled with a liquid of high vapor pressure such as liquified carbon dioxide or the like. Most conveniently the pressure source 11 is of the type provided with an integral needle valve 15 at the top thereof to which the reservoir 10 may be affixed by means of the nipple 12. A flow of gas from the source 11 to the reservoir may be controlled by the needle valve 15 by the simple twisting of the reservoir and gas source in relationship to each other.

Also in Fig. 1 the nozzle 16 is shown projecting from the cap member 17 affixed to the reservoir 10. The cap member 17 is provided with a projecting collar 18 flattened on two sides as shown in Figs. 2 and 3 to permit the engagement thereof with a suitable wrench.

The liquid insecticides, lacrimators, irritants or the like or the suspension of powdered insecticides, lacrimators, irritants or the like which are adaptable to usage in the projecting apparatus of my invention can normally be purchased in cylindrical containers such as the container 25 shown in Fig. 2 which is a sectional elevation of the projecting apparatus with the pressure source 11 eliminated. As shown in Fig. 2 such a container 25 is placed within the reservoir 10 with the bottom thereof closed and the cap removed. The reservoir 10 is of such dimensions as to provide a relatively small annular space 26 between the walls of the container 25 and of the reservoir 10. The bottom member 28 is affixed to the reservoir 10 by suitable threads or the like and is provided with the aforementioned nipple 12 whereby the valve 15 of the pressure cylinder 11 as shown in Fig. 1 may be affixed to the reservoir. The bottom closure 28 is provided with a passageway 29 communicating between the pressure source 11 and the interior of the reservoir 10.

Disposed within the reservoir 10 and abutting against the closure member 28 is the helical spring 30 which exerts an upward force on the container 25 so as to cause the lip 31 of the container 25 to abut against the circular gasket 32 provided in the cap member 17, so as to form a seal therewith.

Gas released from the cylinder 11 by the twisting of the reservoir 10 with relation to the pressure cylinder and thereby opening the valve 15, flows through the passageway 29 and upwardly around the container 25 through the annular space 26.

The cap 17 is provided with threads 33 which engage the threads 34 of the reservoir 10. As

shown in Fig. 2 the cap 17 projects within the reservoir 10 an appreciable distance and the projection of the cap is provided with a circumambient groove 36. Projecting radially inwardly from the groove 36 is a bore 38 which is in communication with the upper opening of the container 25 by means of the perpendicular bore 39. The lower face of the cap 17 is adapted to receive an eduction tube 40 affixed thereto by means of the threads 41 or the like. The upper face of the cap 17 is adapted to receive the nozzle 16 hereinafter more fully described. A passageway 44 is provided in the cap member 17 communicating between the upper end of the eduction tube 40 and the lower end of the nozzle 16. The passageway 44 may be considered and is so considered hereinafter as an integral part of the eduction tube 40.

A bypass orifice 45 is provided in communication with the radial bore 38 and the passageway 44 and is of smaller diameter than the bore 39 communicating between the bore 38 and the bore and the upper opening of the container 25.

Projecting radially and diametrically opposite to the above mentioned bore 38 is a bore 46 threaded at the outer end to engage a set screw 48 which controls the compressive force applied to a helical spring 50 residing within the bore 46. The helical spring 50 exerts a compression force on a ball valve 51 residing in the passageway 44 at the point of entrance of the orifice or bypass tube 45. The ball valve 51 is adapted to seat in its closed position against the orifice 45 and against the opening of the eduction tube 40. Thus when no pressure or only a small amount of pressure is supplied to the reservoir through the passageway 29 of the nipple 12 the compressive force of the spring 50 is maintained sufficiently high to cause the ball valve 51 to seat as above described and thereby prevent the flow of gas through the orifice 45 and the flow of liquid through the eduction tube 40.

By varying the position of the set screw 48 and thus the compressive force exerted by the spring 50 on the check valve 51 the apparatus can be caused to shut off at any predetermined pressure and further the pressure differential existing between the gas flowing through the orifice 45 and the gas flowing into the container 25 may be automatically controlled so as to be substantially constant regardless of variations in pressure of the pressure source or pressure motivating fluid. The advantages accruing from the ability to maintain such a constant differential pressure equilibrium and further to prevent the flow of any fluid or any gas or liquid below a predetermined driving pressure are immediately obvious. By virtue of this feature of the apparatus the liquid spray may be maintained substantially constant regardless of variation of pressure in the pressure source and may be stopped completely and leakage prevented when the pressure in such source falls below a level sufficient to unseat the ball valve 51. This minimum pressure required to unseat the regulating valve 51 is a function of the compression of the spring 50 by the set screw 48 and may be readily adjusted in accordance with the type of pressure fluid to be employed and other variable conditions.

The nozzle 16 is provided with a helical core 54. To preclude the passage of the liquid discharged from the reservoir centrally through the nozzle 16 the core is formed with a diameter

slightly in excess of the internal radius of the nozzle. Thus the helical core prevents any straight flow through the tube 16 and provides for ejection of the suspension from the nozzle with a spiral as well as a linear velocity. Thus as the jet is issuing from the nozzle it has three motions: linear and rotational or helical as well as the motion due to the expanding and rotating jet which is spiral at any given point, hence this motion could be termed a "helical-spiral-velocity."

As an example the nozzle 16 may be rifled with two or three turns per inch of the helical core 54. When using carbon dioxide as the source of pressure linear velocity of the gas driven liquid through the nozzle will be approximately 1000 feet per second. Hence, the rotational velocity will be between 24,000 and 36,000 R. P. M. Thus the liquid is discharged from the nozzle at a high linear and rotational velocity, affording the greatest possible range with the least loss and with practically no dispersion of the irritant agent in the vicinity of the operator.

In Fig. 3 a plan view of the apparatus is shown. In this figure it is seen that the cap 17 is provided with the threads 33 and the circumferential groove 36 from which the radial bore or passageway 38 and the orifice or bypass 45 project inwardly. Diametrically opposite the bore 38 is the radial bore 46 in which is disposed the set screw 48 maintaining the helical spring 50 against the regulating valve 51 shown in Fig. 2.

Having described the structural details of this embodiment of the invention its operation is as follows:

The pressure receptacle 11 is charged with air or an inert gas or a liquid of high vapor pressure to approximately 1000 lbs. per square inch and the container 25 containing the desired liquid to be projected is inserted in the reservoir 10. The reservoir 10 is affixed to the valve 15 of the pressure cylinder 11 by means of the nipple arrangement 12 and is held in position by the set screws 13 and 14. These set screws 13 and 14 permit the twisting of the reservoir 10 with relation to the pressure cylinder 11 without exerting force on the threads of the nipple, i. e. without unscrewing or excessively tightening the reservoir with relation to the pressure cylinder.

Upon exerting a small twisting force on either the reservoir or the pressure cylinder the needle valve 15 positioned in the upper portion of the cylinder 11 is opened and the gas escaping therefrom flows through the passageway 29 into the lower portion of the reservoir 10, passes around the outside of the container 25 in the annular space 26 and passes upwardly past the upper end of the container 25, and the gasket 32, into the circumferential groove 36 in the cap member 17. From this circumferential groove 36 the gas is forced through the radial bore 38 and the vertical bore 39 into a liquid container 25, causing the discharge of liquid from the container through the eduction tube 40 and the nozzle 16. A portion of the gas flowing through the bore 38 proceeds directly through the bypass 45 into the eduction tube. Thus the liquid will be discharged providing that the combined force acting upon the valve 51 from the gas flowing through the orifice 45 and the liquid in the eduction tube 40 is sufficient to unseat the valve. The effect of the gas bypassing the container 25 through the orifice or bypass 45 is to accelerate the velocity of liquid flow through the nozzle 16

and project same with a high forward and rotational velocity.

Another modification of the apparatus of the invention is shown in elevation in Fig. 4 and in a fragmentary sectional elevation in Fig. 5. This apparatus differs from that heretofore described in the provision of the pressure cylinder 11 communicating with the side of the reservoir 10 rather than through the bottom thereof. In this apparatus the container 25 rests on the spring 30 supported on the bottom 28 of the reservoir 10. The bottom 28 may be permanently affixed to the reservoir either by threads as shown or by welding or the like. A support means 60 may be clamped to the pressure source 11 so as to support the reservoir 10 in the proper relationship to the pressure source 11. The cylinder 11 is provided with the needle valve 15 and the control of the flow of pressure fluid 11 into the reservoir 10 may be accomplished by the simple twisting of the cylinder 11 as above described.

In this apparatus as shown in Fig. 5 the nipple communicating between the reservoir and the cylinder 11 constitutes an integral part of the side of the reservoir 10. This nipple 62 communicates directly with the bore 38 proceeding radially from the circumferential groove 36 and thus provides for the same action as described in relation to the above described apparatus.

The gas flowing through the bore 38 is divided a part flowing through the bore 39 into the top of the container 25 which is forced against the gasket 32, by the spring 30, and a part flows through the bypass bore 45 directly into the eduction tube 40. Here again the operation of the device is dependent upon the compressive force exerted by the spring 50 on the ball valve 51 which in turn is a function of the tension placed on the spring by the set screw 48 disposed in the radial bore hole 46.

As shown in Fig. 1, there is provided the tube 64 communicating between the needle valve 15 of the pressure source 11 and the nipple 62 forming an integral part of the reservoir 10. The tube 63 is affixed to the needle valve 15 by means of the coupling 65 and the nipple 62 by means of the coupling 66.

It will be immediately apparent that many mechanical variations in the liquid projecting apparatus of the invention may be made without departing from the scope of the foregoing description or of the following claims.

I claim:

1. A liquid projecting apparatus comprising a cylindrical reservoir provided with a cap member and a closure at its lower end, said closure forming a nipple, a source of gas under pressure adapted to engage with said nipple, means for affixing said source to said nipple to permit the exertion of a propelling force between said source of gas under pressure and said reservoir, a liquid container open at its upper end and closed at its lower end positioned within said reservoir, so as to provide an annular space between said container and said reservoir, a helical spring positioned in said reservoir between the bottom thereof and the bottom of said liquid container so as to force said liquid container to abut against a gasket member provided in said cap member, said cap member being further provided with a circumferential slot, a pair of diametrically opposed radial bores projecting inwardly from said circumferential slot, a vertical bore communicating between the upper end of said container

and one of said radial bores, an orifice communicating between said last mentioned radial bore and an eduction tube projecting through said cap member and terminating below the surface of the liquid in said container, a nozzle projecting from said cap member and in communication with said eduction tube, and a regulating valve disposed within said eduction tube adjacent to said orifice.

2. An apparatus according to claim 1 wherein said regulating valve is maintained within said eduction tube by means of a helical spring disposed within the said other of said radial bores.

3. An apparatus according to claim 2 wherein said regulating valve is maintained within said eduction tube by means of a helical spring disposed within the said other of said radial bores, the compression force of said helical spring being variably responsive to the setting of a set screw disposed within said other of said radial bores.

4. A liquid projecting apparatus comprising a reservoir provided with a cap member and a closure at its lower end, a liquid container open at its upper end and closed at its lower end positioned within said reservoir, a helical spring positioned in said reservoir between the bottom thereof and the bottom of said liquid container so as to force said liquid container to abut against a gasket member provided in said cap member, said cap member being further provided with a circumferential slot, a pair of diametrically opposed radial bores projecting inwardly from said circumferential slot, a vertical bore communicating between the upper end of said container and one of said radial bores, an orifice communicating between said last mentioned radial bore and an eduction tube projecting through said cap member and terminating below the surface of the liquid in said container, a nozzle projecting from the said cap member and in communication with said eduction tube, a regulating valve disposed within said eduction tube adjacent to said orifice, a nipple member located in the wall of said reservoir in communication with said first mentioned radial bore, and a source of gas under pressure adapted to engage with said nipple.

5. An apparatus according to claim 4 wherein said regulating valve is maintained within said eduction tube by means of a helical spring disposed within the said other of said radial bores.

6. An apparatus according to claim 4 wherein said regulating valve is maintained within said eduction tube by means of a helical spring disposed within the said other of said radial bores, the compression force of said helical spring being variably responsive to the setting of a set screw disposed within said other of said radial bores.

7. A liquid projecting apparatus comprising a reservoir provided with a cap member and a closure at its lower end, a liquid container open at its upper end and closed at its lower end positioned within the reservoir, a helical spring positioned in the reservoir between the bottom thereof and the bottom of the liquid container, so as to force the liquid container to abut against a gasket member provided in the cap member, the cap member being further provided with a circumferential slot, a pair of diametrically opposed radial bores projecting inwardly from said circumferential slot, a vertical bore communicating between the upper end of the container and one of the radial bores, a restricted orifice communicating between the last mentioned radial bore

and an eduction tube projecting through the cap member and terminating below the surface of the liquid in the container, a nozzle projecting through the cap member and in communication with the eduction tube, a regulating valve disposed within the eduction tube adjacent the orifice, a source of gas under pressure, and means communicating between the source of gas under pressure and said one of said radial bores.

8. A liquid projecting apparatus comprising a reservoir provided with a cap member and having a closure at its lower end, said closure forming a nipple, a source of gas under pressure adapted to engage with the nipple, a liquid container open at its upper end and closed at its lower end positioned within the reservoir, a helical spring positioned in said reservoir between the bottom thereof and the bottom of said liquid container so as to force said liquid container to abut against a gasket member provided in the cap member, said cap member being further provided with a circumferential slot, a pair of diametrically opposed radial bores projecting inwardly from said circumferential slot, a vertical bore communicating between the upper end of said container and one of said radial bores, a restricted orifice communicating between said last mentioned radial bore and an eduction tube projecting through said cap member and terminating below the surface of the liquid in said container, a nozzle projecting into the cap member and in communication with the eduction tube, a regulating valve disposed in said eduction tube adjacent the orifice.

9. A liquid projecting apparatus comprising a reservoir provided with a cap member and a closure at its lower end, a liquid container open at its upper end and closed at its lower end positioned within the reservoir, a helical spring positioned in said reservoir between the bottom thereof and the bottom of said liquid container so as to force said liquid container to abut against a gasket member provided in the cap member, said cap member being further provided with a circumferential slot, a pair of diametrically opposed radial bores projecting inwardly from said circumferential slot, a vertical bore communicating between the upper end of said container and one of said radial bores, a restricted orifice communicating between said last mentioned radial bore and an eduction tube projecting through said cap member and terminating below the surface of the liquid in said container, a nozzle projecting into the cap member and in communication with the eduction tube, a regulating valve disposed in said eduction tube adjacent the orifice, a nipple member located in the wall of said reservoir in communication with said first mentioned radial bore, and a source of gas under pressure adapted to engage with said nipple.

10. A liquid projecting apparatus comprising a reservoir provided with a cap member and a closure at its lower end, a liquid container open at its upper end and closed at its lower end positioned within the reservoir, a helical spring positioned in the reservoir between the bottom thereof and the bottom of the liquid container, so as to force the liquid container to abut against a gasket member provided in the cap member, the cap member being further provided with a circumferential slot, a pair of diametrically opposed radial bores projecting inwardly from said circumferential slot, a vertical bore communicating between the upper end of the container and one of the radial bores, a restricted orifice communicating between the last mentioned radial bore

nicipating between the last mentioned radial bore and an eduction tube projecting through the cap member and terminating below the surface of the liquid in the container, a nozzle projecting through the cap member and in communication with the eduction tube, a ball in the eduction tube seating against the orifice and adapted to close the orifice and tube and spring loaded against the orifice, a source of gas under pressure, and means communicating between the source of gas under pressure and said one of said radial bores.

11. A liquid projecting apparatus comprising a reservoir provided with a cap member and a closure at its lower end, a liquid container open at its upper end and closed at its lower end positioned within the reservoir, a helical spring positioned in the reservoir between the bottom thereof and the bottom of the liquid container, so as to force the liquid container to abut against a gasket member provided in the cap member, the cap member being further provided with a circumferential slot, a pair of diametrically opposed radial bores projecting inwardly from said circumferential slot, a vertical bore communicating between the upper end of the container and one of the radial bores, a restricted orifice communicating between the last mentioned radial bore and an eduction tube projecting through the cap member and terminating below the surface of the liquid in the container, a nozzle projecting through the cap member and in communication with the eduction tube, a ball in the eduction

tube adjacent the orifice adapted to seat against the orifice and in the eduction tube to prevent liquid flow through the tube and gas flow through the orifice, a helical spring in the other of said radial bores bearing against the ball, a set screw in the outer end of the last mentioned bore holding the spring in the bore and providing means for adjusting the spring tension on the ball, a source of gas under pressure, and means communicating between the source of gas under pressure and said one of said radial bores.
